NEUTRALIZING ALIPHATIC ACIDS CONTAINING FROTH-PRODUCING SUBSTANCES

Camille Dreyfus, New York, N. Y., and Clifford I. Haney, Drummondville, Quebec, Canada, assignors to Celanese Corporation of America, a corporation of Delaware

No Drawing. Application July 11, 1930
Serial No. 467,391

11 Claims. (Cl. 260—112)

This invention relates to the neutralization of relatively dilute solutions of lower aliphatic acids, particularly acetic acid, which contain froth producing substances, by means of alkaline materials 5 to form metallic salts of such acids.

An object of our invention is to form metallic salts by the neutralization with alkaline materials of relatively dilute solutions of acetic acid or other lower aliphatic acids in an economical 10 and expeditious manner.

A further object of our invention is to form alkali-metal acetates by the neutralization of the relatively dilute acetic acid obtained when water is added to solutions of cellulose acetate in acetic 15 acid to precipitate the cellulose acetate. Further objects of our invention will appear from the following detailed description.

In the formation of cellulose acetate or other organic esters of cellulose, the usual manner is 20 to esterify the cellulose in the presence of the anhydride of the lower fatty acid corresponding to the cellulose ester to be formed and also in the presence of such lower fatty acid. When esterification is complete, the cellulose ester dissolves 25 in the lower fatty acid present. In order to precipitate the cellulose ester, there is added at a subsequent stage of the process, water in sufficient quantities to dilute the acid until it no longer retains the cellulose ester in solution, and 30 the dilute acid is separated from the precipitated cellulose ester.

However such dilute acid contains, either in suspension or in solution, certain organic matters that cause frothing when sodium carbonate 35 is added thereto at room temperatures even while stirring. The froth so formed persists for hours and interferes with the further working up of a solution of the metal salt thus formed on a commercial scale. Heretofore it has been the practice to distil the lower fatty acid, such as acetic 40 acid, from such waste organic material, and then to neutralize the distillate. This distillation involves great expense, and moreover, even when copper stills are employed, the acid attacks the 45 stills so that they depreciate rapidly.

We have found that if such dilute lower fatty acid is neutralized, say with sodium carbonate, while at elevated temperatures, that the froth produced tends to break down quite readily, so 50 that at such elevated temperatures, the neutralization can be carried out quickly enough for practical purposes. Contrary to expectation, there is no appreciable loss of acetic acid or other relatively volatile lower fatty acid during the neutralizing of the hot acid, owing to the fact 55 that the froth that is formed acts as a fractionating column which permits only water vapor and carbon dioxide to escape into the air.

In accordance with our invention, we neutralize relatively dilute solutions of lower fatty acids 60 which contain froth-producing impurities by heating the same at elevated temperatures and then neutralizing them at such temperatures with an alkaline material, and then after settling, subjecting the solution to evaporation to recover the 65 salts of the fatty acids. While at present this invention is of greatest importance in connection with the neutralization of dilute acetic acid obtained after the acetylation of cellulose, it is applicable to solutions of other lower fatty acids 70 such as formic acid, propionic acid or butyric acid. The invention is not confined to the neutralization of such acids as are obtained from the esterification of cellulose, but is also applicable to the 75 neutralization of such acids obtained in any manner. By relatively dilute solutions of the acids we intend to include solutions of 5 to 50% or more concentration and particularly aqueous solutions of such acids.

As stated the relatively dilute solutions of the 80 acids are heated at elevated temperatures, say above 60° C., preferably between 90° and 100° C. The dilute acid solutions may be heated in a batch process in vessels of copper, wood, stainless steel and the like. If desired the process may be a 85 continuous one and this may be done by passing the solutions of the fatty acids through tubes or coils that are heated to the neutralizing vat.

For neutralizing the lower fatty acid, we prefer 90 to use sodium carbonate for economical reasons. However other carbonates such as of potassium or calcium may be used as may the bi-carbonates of sodium and potassium.

During the neutralization of the acid liquor, the 95 organic products that are soluble in the dilute acid separate from the solution in a very fine form. Often some of this organic material is so fine that it does not settle out completely from the liquor, so that upon decantation it remains in the neutralized liquor and causes frothing of the 100 same when it is evaporated. In such cases, we have found it preferable to add to the liquor being neutralized small quantities of coagulating agents such as soluble salts of aluminum and iron, examples of which are alum, aluminum sulfate, 105 ferrous sulfate, ferric sulfate or the double salt of aluminum and ferric sulfate. As soon as the liquor becomes slightly alkaline at the end of neutralization, these iron or aluminum compounds precipitate out as hydroxides and act as coagulants to bring down these organic bodies. In many cases there are enough organic impurities present in the dilute acid which precipitate out on neutralizing and act as coagulants for the fine 110 organic precipitate, in which case the addition of other coagulants is not absolutely necessary.

Neutralized liquor produced in accordance with this invention usually clears in 12 hours or less and it is ready to be evaporated in a concentrating evaporator. During this relatively short settling time, the liquor does not cool to room temperatures, but about one-half of the heat is retained in the liquor when evaporation is commenced.

If the dilute acid to be neutralized, say acetic acid obtained from the precipitation of cellulose acetate, contains sulfuric acid that may have been employed as a catalyst, the same may be treated with the carbonate or hydroxide of barium to precipitate barium sulfate. However the removal of sulfuric acid is not absolutely necessary, since the sodium sulfate or potassium sulfate formed during neutralization does not form any scale in the evaporators.

In order further to illustrate our invention but without being limited thereto, the following specific example is given.

Example

Dilute acetic acid obtained from the precipitation of cellulose acetate by the addition of water to the acetylation mixture, and having a concentration of say 20%, is heated in a copper or wood container by means of a closed steam coil until it attains a temperature of 90 to 95° C. When this temperature is reached, the acid is run into a wooden neutralizing vat provided with a mechanical agitator and a small open steam connection. As soon as the acid liquor starts to run into the vat, agitation is commenced and a small amount of steam is injected into the liquor through the open steam connection to make up for the heat lost from the liquor to the vat and by radiation. The temperature of the acid is maintained around 90° C.

While the acid is running into the vat the addition of soda ash (sodium carbonate) is commenced and additions of both the acid and soda ash is carried on in such a manner that the liquor in the neutralizing vat is kept almost at the neutral point. When the neutralizing vat is filled, aluminum sulfate in amounts equal to about 0.015% of the liquor present is added. The aluminum sulfate is usually added in the form of a solution in a small amount of water. The liquor in the vat is then tested and adjustments are made so that it has a slightly alkaline reaction corresponding to an excess of 0.05 to 0.1% of sodium carbonate.

The agitation is stopped after several minutes, and the liquor in the vat allowed to stand, whereupon the precipitates settle, and after 12 hours or even less time, a liquor 7 or 8 feet deep will have cleared. The sludge that collects at the bottom of the vat is not disturbed and the clear liquor is drawn off for evaporation. During the evaporation no difficulty with frothing is encountered. Without cleaning the vat, a number of operations may be performed, allowing the sludge to settle each time, until it becomes several inches deep, whereupon the sludge is removed and a fresh series of operations commenced.

It is to be understood that the foregoing example is given merely by way of illustration and that many variations may be made therein without departing from the spirit of our invention.

Having described our invention, what we desire to secure by Letters Patent is:

1. Method of neutralizing a relatively dilute lower aliphatic acid containing a froth-producing substance comprising treating the same at a tem-

perature above 60° C. with an alkaline substance which generates gas upon neutralizing the acid.

2. Method of neutralizing relatively dilute acetic acid containing a froth-producing substance comprising treating the same at a temperature above 60° C. with an alkaline substance which generates gas upon neutralizing the acid.

3. Method of neutralizing a relatively dilute lower fatty acid recovered from the reaction mass resulting from the esterification of cellulose and containing a froth producing substance comprising treating the same at a temperature above 60° C. with an alkaline substance which generates gas upon neutralizing the acid and then settling the resulting liquor.

4. Method of neutralizing relatively dilute acetic acid recovered from the reaction mass resulting from the esterification of cellulose and containing a froth producing substance comprising treating the same at a temperature above 60° C. with an alkaline substance which generates gas upon neutralizing the acid and then settling the resulting liquor.

5. Method of neutralizing relatively dilute acetic acid recovered from the reaction mass resulting from the acetylation of cellulose and containing a froth-producing substance comprising treating the same with an alkaline carbonate at temperatures above 60° C. and then permitting the resulting liquor to settle.

6. Method of neutralizing relatively dilute acetic acid recovered from the reaction mass resulting from the acetylation of cellulose and containing a froth-producing substance comprising treating the same with an alkaline carbonate at temperatures between 90° and 100° C. and then permitting the resulting liquor to settle.

7. Method of neutralizing a relatively dilute lower fatty acid containing a froth-producing substance comprising neutralizing the same at a temperature above 60° C. with an alkaline substance which generates gas upon neutralizing the acid, there being present a coagulant in at least the last stage of the neutralization.

8. Method of neutralizing relatively dilute acetic acid containing a froth-producing substance comprising neutralizing the same at a temperature above 60° C. with an alkaline substance which generates gas upon neutralizing the acid, there being present a coagulant in at least the last stage of the neutralization.

9. Method of neutralizing relatively dilute acetic acid recovered from the reaction mass resulting from the acetylation of cellulose and containing a froth-producing substance comprising treating the same at a temperature above 60° C. with an alkaline carbonate and towards the end of the reaction adding a coagulant thereto.

10. Method of neutralizing relatively dilute acetic acid recovered from the reaction mass resulting from the acetylation of cellulose and containing a froth-producing substance comprising treating the same at a temperature above 60° C. with an alkaline carbonate and towards the end of the reaction adding a soluble iron compound.

11. Method of neutralizing relatively dilute acetic acid recovered from the reaction mass resulting from the acetylation of cellulose and containing a froth-producing substance comprising treating the same at a temperature above 60° C. with an alkaline carbonate and towards the end of the reaction adding a soluble aluminum compound.
